Primary Examiner — Samantha Wood

(57) **CLAIM**

The ornamental design for a watch, substantially as shown and described.

DESCRIPTION

FIG. 1 is a top, perspective view of the watch; the view showing my new design;

FIG. 2 is a top, perspective view thereof;

FIG. 3 is a top, perspective view thereof;

FIG. 4 is a side view thereof;

FIG. 5 is a side view thereof;

FIG. 6 is a top view thereof;

FIG. 7 is a bottom view thereof;

FIG. 8 is a front view thereof;

FIG. 9 is a back view thereof; and,

FIG. 10 is a bottom, perspective view thereof.

The broken lines showing portions of the design in the figures are included for the purpose of illustrating environment and unclaimed features and forms not part of the claimed design.

1 Claim, 8 Drawing Sheets(56)
